Attorney.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

HEDDLE FRAME

Application filed February 24, 1930. Serial No. 430,474.

My invention relates to heddle frames for looms, and it relates more particularly to improved means, in a heddle frame of the usual type, for supporting the heddle bars intermediate their ends.

The principal object of my present invention is to provide, in a heddle frame, improved means for supporting the heddle bars intermediate their ends, which will securely support said bars against undesirable motion and displacement, but which, however, will permit the bars to be quickly and conveniently mounted in and dismounted from the frame when desired.

15 My present invention contemplates an improved form of supporting device which may be readily adjusted with respect to the top and bottom rails of the frame, so that the heddle supporting bars will be properly positioned and the heddles will not bind thereon, nor, on the other hand, be permitted too great an up and down movement thereon.

25 My present invention further contemplates an improved form of supporting device in which a relatively large bearing surface will be provided for the heddle supporting bars, and in which said bars will be held against movement under proper spring tension, whereby wear on the bars at the points of support will be reduced to a minimum.

30 My present invention further contemplates certain improved details of construction, whereby the device will be rendered more durable and efficient.

35 The nature and characteristic features of my invention will be more readily understood from the following description, taken in connection with the accompanying drawings forming part hereof, in which:

40 Figure 1 is an elevational view of a heddle frame provided with heddle bar supporting devices embodying the main features of my present invention;

45 Fig. 2 is an enlarged section taken approximately on the line 2-2 of Fig. 1, the parts being shown in the normal positions assumed while supporting the heddle bars;

50 Fig. 3 is an enlarged fragmentary side elevation illustrating one of the supporting devices, the same being shown in conjunction

with a portion of the rail of the heddle frame in which it is mounted;

55 Fig. 4 is a view similar to Fig. 2, but looking from the opposite side and with the parts in the open position for the purpose of removing the heddle bars therefrom or mounting the same therein;

60 Fig. 5 is a vertical central section of one of the supporting devices, the parts being shown in the open position;

65 Fig. 6 is a perspective view of a bolt member forming a component part of the device, the other parts being removed therefrom; and

Fig. 7 is a perspective view of a slidable locking member constituting one of the component parts of the device.

70 It will, of course, be understood that the drawings and description herein contained are illustrative merely, and that various modifications and changes may be made in the structure disclosed without departing from the spirit of my invention.

75 Referring to the drawings, the heddle frame there shown comprises top and bottom rails 10, connected at their ends by means of side strips 11. Extending from end to end of the heddle frame, and arranged near the top and bottom rails 10, are the heddle bars 12, on which the heddles 13 are mounted in the usual manner.

80 The devices comprising the novel portion of the present invention are mounted at suitable locations on the inner edges of the top and bottom rails 10. Each of these devices, 85 as shown in the drawings, includes a bolt member 20 having a shank 21, the end of which is threaded as at 22, in a manner similar to that of an ordinary wood screw, with the exception that the same is not tapered the greater portion of its length.

85 The bolt member 20 is also provided with a head portion 23, preferably made by flattening and spreading the material of the rod from which the bolt member is formed. To- 95 toward the end of the flattened head portion of the bolt member 20, there are provided shoulders 24.

90 On each side of the flattened head portion 23 of the bolt member 20 there is mounted a 100

plate 30. The plates 30 may be secured to the head portion 23 of the bolt member 20 by means of rivets 31, or other suitable fastening devices.

Each of the plates 30 is provided with recesses 32. The recesses 32 are of slightly greater width than the width of the heddle supporting bars 12 which are adapted to be mounted therein, and the surfaces thereof 10 upon which the heddle supporting bars 12 rest form continuations of the corresponding surfaces of the head portion 23 of the bolt member 20, as well as the shoulders 24 thereof.

15 A slideable locking member 40 is mounted on the bolt member 20, being so shaped as to provide a horizontal portion 41 having an aperture 42 complementary to the shank of the bolt member 20. The slideable locking member 40 is also provided with vertical legs 20 43, straddling the head portion 23 of the bolt member 20.

The leg portions 43 of the slideable locking member 40 are guided between the plates 30 25 which are secured to the head portion 23 of the bolt member 20. The lower end of each of the leg portions 43 is provided with a lip 44, which is adapted to extend down over the outside of the heddle supporting bar 12.

30 A coil spring 50 is mounted on the shank 21 of the bolt member 20. The coil spring 50 bears at one end against the horizontal portion 41 of the slideable locking member 40, and bears at its other against struck up portions 25.

35 The struck up portions 25, being integral with the shank 21 of the bolt member 20, will thereby be fixedly located, so that the tension of the spring 50 will not be varied when the bolt is adjusted in the rail 10. For the same reason, the rail 10 is provided with a recess 15 of sufficient depth so that the spring 50 will not bear against the inner surface thereof.

40 By the foregoing arrangement, relatively 45 broad bearing surfaces will be provided for the heddle bars, these surfaces being of an extent corresponding to the thickness of the head portion 23 of the bolt member 20, plus the thickness of the two plate members 30 50 which are secured thereto. By this arrangement wear on the heddle bars at the points of support will be reduced to a minimum.

It will also be noted that the slideable locking member bears against the heddle bar at 55 all times, so that movement of the same in the supporting device as the shedding takes place will be minimized, in this manner also reducing wear on the heddle bars.

Should it be found at any time that the 60 heddle bars 12 are so located that undue tension is placed upon the heddles, whereby the same will bind upon the heddle supporting bars, or, on the other hand, should it be found that the heddle supporting bars are so positioned that the heddles are permitted too

much up and down movement in the frame, proper adjustment of the device for supporting the heddle bars may be made by first removing the heddle bar from the supporting device, and then threading the bolt in and out with respect to the rail 10 in which it is mounted, until the head portion 23 of the bolt member 20 is properly located. Such adjustment, however, will not vary the tension of the springs 50.

70 I claim:

1. In a heddle frame, means for supporting the heddle bars intermediate their ends comprising a bolt member adjustably mounted in the heddle frame rail, said bolt member having a flattened head portion, plates secured on each side of the flattened head portion of the bolt, said plates having recesses in which the heddle bars are adapted to be seated, and a slideable locking member mounted upon the bolt member having leg portions straddling the flattened head portion thereof and guided between the plate members, the leg portions of said slideable locking member having lips extending over the outside of the heddle bars when said member is in the locking position.

75 2. In a heddle frame, means for supporting the heddle bars intermediate their ends comprising a bolt member adjustably mounted in the heddle frame rail, said bolt member having a flattened head portion, plates secured on each side of the flattened head portion of the bolt, said plates having recesses in which the heddle bars are adapted to be seated, a slideable locking member mounted upon the bolt member having leg portions straddling the flattened head portion thereof and guided between the plate members, the leg portions of said slideable locking member having lips extending over the outside of the heddle bars when said member is in the locking position, and a spring for impelling the slideable locking member to the locking position.

80 3. In a heddle frame, means for supporting the heddle bars intermediate their ends comprising a bolt member adjustably mounted in the heddle frame rail, said bolt member having a flattened head portion provided with shoulders upon which the heddle bars are adapted to be seated, plates secured on each side of the flattened head portion of the bolt, said plates having recesses in which the heddle bars are adapted to be seated, the bearing surfaces of said recesses corresponding to the bearing surfaces of the flattened head portion of the bolt member, a slideable locking member mounted upon the bolt member having leg portions straddling the flattened head portion thereof and guided between the plate members, the leg portions of

85 100 105 110 115 120 125 130 135

said slideable locking member having lips extending over the outside of the heddle bars when said member is in the locking position,

and a spring for impelling the slidable locking member to the locking position.

4. In a heddle frame, means for supporting the heddle bars intermediate their ends comprising a bolt member threaded directly into the heddle frame rail, said bolt member having a flattened head portion, plates secured on each side of the flattened head portion of the bolt, said plates having recesses in which the heddle bars are adapted to be seated, a slidable locking member mounted upon the bolt member having leg portions straddling the flattened head portion thereof and guided between the plate members, the leg portions of said slidable locking member having lips extending over the outside of the heddle bars when said member is in the locking position, and a spring for impelling the slidable locking member to the locking position.

5. In a heddle frame, means for supporting the heddle bars intermediate their ends comprising a bolt member threaded directly into the heddle frame rail, said bolt member having a flattened head portion provided with shoulders upon which the heddle bars are adapted to be seated, plates secured on each side of the flattened head portion of the bolt, said plates having recesses in which the heddle bars are adapted to be seated, the bearing surfaces of said recesses corresponding to the bearing surfaces of the flattened head portion of the bolt member, and a slidable locking member mounted upon the bolt member having leg portions straddling the flattened head portion thereof and guided between the plate members, the leg portions of said slidable locking member having lips extending over the outside of the heddle bars when said member is in the locking position.

6. In a heddle frame, means for supporting the heddle bars intermediate their ends comprising a bolt member threaded directly into the heddle frame rail, said bolt member having a flattened head portion provided with shoulders upon which the heddle bars are adapted to be seated, plates secured on each side of the flattened head portion of the bolt, said plates having recesses in which the heddle bars are adapted to be seated, the bearing surfaces of said recesses corresponding to the bearing surfaces of the flattened head portion of the bolt member, a slidable locking member mounted upon the bolt member having leg portions straddling the flattened head portion thereof and guided between the plate members, the leg portions of said slidable locking member having lips extending over the outside of the heddle bars when said member is in the locking position, and a coil spring mounted on the bolt member for impelling the slidable locking member to the locking position.

7. In a heddle frame, means for supporting the heddle bars intermediate their ends

comprising a bolt member threaded directly into the heddle frame rail, said bolt member having a flattened head portion provided with shoulders upon which the heddle bars are adapted to be seated, plates secured on each side of the flattened head portion of the bolt, said plates having recesses in which the heddle bars are adapted to be seated, the bearing surfaces of said recesses corresponding to the bearing surfaces of the flattened head portion of the bolt member, a slidable locking member mounted upon the bolt member having leg portions straddling the flattened head portion thereof and guided between the plate members, the leg portions of said slidable locking member having lips extending over the outside of the heddle bars when said member is in the locking position, and a coil spring mounted on the bolt member, said coil spring bearing at one end against the slidable locking member and the bolt member having a fixedly located extension against which the other end of said coil-spring bears.

8. In a heddle frame, means for supporting the heddle bars intermediate their ends comprising a bolt member adjustably mounted in the heddle frame rail, said bolt member having a flattened head portion provided with shoulders upon which the heddle bars are adapted to be seated, plates secured on each side of the flattened head portion of the bolt, said plates having recesses in which the heddle bars are adapted to be seated, the bearing surfaces of said recesses corresponding to the bearing surfaces of the flattened head portion of the bolt member, and a slidable locking member for retaining the heddle bars in said recesses.

In testimony whereof, I have hereunto signed my name.

JOHN JACOB KAUFMANN.
